UNITED STATES PATENT OFFICE.

THOMAS EARLE HOUSE, OF JACKSON, TENNESSEE.

MEANS FOR CONNECTING CAR-COUPING BUTTS AND YOKES.

Application filed June 15, 1922. Serial No. 568,477.

To all whom it may concern:

Be it known that I, THOMAS E. HOUSE, a citizen of the United States, residing at Jackson, in the county of Madison and 5 State of Tennessee, have invented certain new and useful Improvements in Means for Connecting Car-Coupling Butts and Yokes, of which the following is a specification.

My invention has for its object the provision of simple and inexpensive means whereby the supporting yoke of a car coupling may be readily attached to the butt of the drawhead in such a manner as to be permanent and avoid the use of rivets or 10 similar devices. As now ordinarily constructed, the supporting yoke has its ends disposed against the outer sides of the butt of the drawhead and riveted thereto. The severe strains to which the device is subjected 15 in coupling and uncoupling cars and in shifting cars quickly wears away the opposed surfaces of the rivets and the parts through which they are fitted so that lost-motion occurs and the rivets are frequently sheared 20 off, necessitating frequent renewals and repairs. My invention provides means for connecting the yoke to the drawbar whereby the use of rivets is avoided and wear upon the parts is minimized if not entirely eliminated. 25 My invention is illustrated in the accompanying drawings and will be hereinafter fully set forth.

In the drawings—

Figure 1 is a plan view of so much of a 30 coupling as is necessary to an understanding of my invention;

Fig. 2 is a vertical section on the line 2—2 of Fig. 1;

Fig. 3 is a detail perspective view of the 40 yoke;

Fig. 4 is a perspective view of one of the keys.

In the drawings, the reference numeral 1 indicates a portion of a shank of a drawbar 45 and 2 indicates the butt of the same which is enlarged as is usual. In the present invention, the butt is provided with vertical openings 3 therethrough, the outer walls of these openings being parallel with the sides 50 of the butt and the inner walls thereof diverging toward the rear end of the butt. The butt is also provided with sockets 4 opening through its rear end and establishing communication between the rear end of the butt 55 and the said vertical openings 3. The yoke 5 is of the usual form, except that its ends

are made somewhat thicker than its sides and taper toward its sides, as shown at 6. The sockets 4 are wide enough to admit the ends of the yoke and at their inner ends define grooves disposed horizontally in the outer walls of the vertical openings or passages 3. After the ends of the yoke are inserted through the sockets 4 and rest against the forward walls of the openings 3, 60 keys 7 are fitted between the inner walls of the said openings and the opposed obliquely disposed surfaces of the yoke and are forced downwardly until their heads 8 rest upon the upper edges of the yoke, as shown clearly 65 in Fig. 2. These keys are relatively thin flat plates, as shown clearly in Fig. 4, and are provided with splits 9 in their lower ends so that, after they have been inserted between the ends of the yoke and the opposed walls 70 of the vertical openings 3, a chisel or other tool may be forced between the lower ends of the keys and the respectively adjacent surfaces of the openings 3 so that the lower extremities of the keys will be bent to form 75 hooks 10 engaging under the ends of the yoke, as shown in Fig. 2. Vertical movement of the yoke is effectually resisted and prevented by the engagement of the heads 8 and hooks 10 with the upper and lower edges 80 respectively of the yoke and by the engagement of the said edges with the upper and lower walls of the sockets 4. Endwise movement of the yoke relative to the drawbar is 85 prevented by the engagement of the keys with the opposed surfaces of the yoke and the drawbar inasmuch as the oblique arrangement of the said opposed surfaces and the keys will cause the keys to have a wedging 90 action upon the yoke under the pulling strain applied to the yoke through the drawbar. My device is exceedingly simple and may be applied to car couplings at a cost 95 so small as to not merit consideration. When applied, it will prove highly efficient 100 and will prolong the life of the coupling and of the yoke and reduce the cost of maintenance and repair to a negligible quantity.

Having thus described the invention, what is claimed as new is:

1. The combination of a drawbar provided with sockets in its butt, a yoke having its ends insertible in said sockets, and keys engageable through the sockets between the sides of the same and the sides of the yoke 110 whereby to bind the parts together.
2. The combination of a drawbar provided

with yoke-receiving sockets opening through the rear end of its butt and with vertically disposed passages communicating with said sockets, a yoke having its ends thickened at their extremities and tapered rearwardly therefrom at their sides, said ends being insertible in the sockets in the butt of the drawbar, and flat keys insertible through the vertical openings in the butt of the drawbar

between the opposed surfaces of said openings and the ends of the yoke, said keys being provided at their upper ends with heads adapted to rest upon the upper edges of the yoke and having their lower ends bendable to engage the lower edges of the yoke. 10

In testimony whereof I affix my signature. 15

THOMAS EARLE HOUSE. [L.S.]
